A. J. CHEVRETT ET AL

WEFT CARRIER SUPPORT AND RELEASING DEVICE

Filed Feb. 2, 1923

UNITED STATES PATENT OFFICE.

AUGUSTIN J. CHEVRETT, OF WORCESTER, AND EPPA H. RYON, OF WALTHAM, MASSACHUSETTS, ASSIGNEES TO CROMPTON & KNOWLES LOOM WORKS, OF WORCESTER, MASSACHUSETTS, A CORPORATION OF MASSACHUSETTS.

WEFT-CARRIER SUPPORT AND RELEASING DEVICE.

Application filed February 2, 1923. Serial No. 616,470.

To all whom it may concern:

Be it known that we, AUGUSTIN J. CHEVRETT and EPPA H. RYON, both citizens of the United States, residing, respectively, at Worcester and Waltham, in the counties of Worcester and Middlesex, and State of Massachusetts, have invented new and useful Weft-Carrier Supports and Releasing Devices, of which the following is a specification.

This invention relates to an improved device for supporting a weft carrier in transfer position in a weft replenishing loom and for releasing said weft carrier upon transfer.

It is the general object of our invention to improve the construction and operation of such devices in certain important respects thereby providing an exceedingly simple and effective support which possesses important advantages when in use.

With this general object in view, our invention relates particularly to the provision of a two-point support and releasing device mounted on the magazine in the upper portion thereof, together with improved devices for both angularly and vertically adjusting said support and the parts thereof.

Our invention further relates to the provision of an improved transverse guide for the support and releasing device and to certain arrangements and combinations of parts which will be hereinafter described and more particularly pointed out in the appended claims.

A preferred form of the invention is shown in the drawings in which—

Fig. 1 is a sectional side elevation, showing parts of a weft carrier magazine embodying our invention;

Fig. 2 is a rear elevation of certain parts shown in Fig. 1;

Fig. 3 is a detail sectional plan view, taken along the line 3-3 in Figs. 1 and 2;

Fig. 4 is a detail plan view, looking in the direction of the arrow 4 in Fig. 1.

Referring to the drawings, we have shown a magazine end frame 10 of the usual stationary type and provided with a bracket 11 by which it may be mounted in fixed position in a loom. Guides or ribs 12 are vertically disposed in the magazine and divide the magazine into a series of vertical com-

partments 13 in which the different kinds of weft carriers are stored. Upon indication of transfer, a selected weft carrier W is released and descends to the transfer position indicated in Fig. 1.

In this position, the front side of the butt of the weft carrier is supported by a fixed guide plate 14 and the front side of the tip of the weft carrier may be yieldingly supported in the usual manner. Our invention relates particularly to improved devices for supporting the weft carrier upon the rear side thereof, said devices engaging the weft carrier only at points substantially removed from the tip portion thereof.

Our improved supporting devices include a vertically extending member 15 having a laterally extending part 16 secured to the upper end thereof and pivoted at 17 to the top of the magazine frame 10. The laterally extending part 16 is preferably offset at its outer end, as indicated in Fig. 4, so that it may be pivoted on the outer side of the frame 10. When mounted in this position, the part 16 does not in any way interfere with the placing of weft carriers in the magazine compartments.

A butt engaging support 18 is secured to the lower end of the member 15 by binding screws 19 and 20 extending through slots 21 in the member 15. A bracket or guide 22 (Fig. 3) is adjustably secured on a cross rod 23 of the magazine and prevents transverse displacement of the support, the bracket being provided with fingers 24 engaging the support on both sides thereof.

The bracket 22 is also provided with an upward extension or web 25 which is engaged by the head of the upper binding screw 20. This screw is threaded in the upper end of the support 18, and may be adjusted therein to vary the position of the support 18 toward or from the weft carrier. The screw 20 also serves as a binding screw by providing a nut 26 on the outer end thereof.

The support 18 has a laterally extending hub or bearing portion 27 in which is adjustably secured an angular rod 28, the outer end of which extends substantially parallel with the support 18 and engages the weft carrier W near the center of its length and

on the rear side thereof. Binding screws 29 in the hub 27 provide for relative angular adjustment between the parts 18 and 28.

The support 18 is also provided with a cam-shaped projection 30 adapted to be engaged by a stud 31 to release the weft carrier W should it remain in transfer position after a transfer has been revoked. For full details in reference to the operation of the 10 stud 31 and to the actuating mechanism, therefor, reference is made to the prior patent to Lauzon, No. 1,261,563, issued April 2, 1918, and to the prior patent to Ryon, No. 1,366,950, issued February 1, 1921. A spring 15 31^a can be interposed between the parts 16 and a projection 32 on the frame 10 to increase the supporting tension of the device if so desired.

Having thus described our invention, it 20 will be seen that we have provided a weft carrier support and releasing device which engages the weft carrier at two points on the rear side thereof, both removed from the tip portion of the weft carrier, that we have 25 provided for relative angular adjustment between the two weft carrier engaging parts of the support, and that we have also provided for simultaneous vertical adjustment of the parts and for simultaneous adjustment thereof toward and from the weft carrier. We have also so designed and constructed our support and releasing device 30 that it swings about a point substantially vertically over the weft carrier to be transferred, the radius of movement being so great that the direction of movement of the engaging parts is substantially in a horizontal plane.

Having thus described our invention and 40 the advantages thereof, we do not wish to be limited to the details herein disclosed otherwise than as set forth in the claims, but what we claim is:—

1. In a loom having a magazine, a weft 45 carrier support and releasing device comprising a vertically disposed member having a part extended laterally and pivoted to said magazine near the top thereof, a two-point engaging device adjustably secured to the lower end of said member and engaging a weft carrier in transfer position at two 50 points on the rear side of said weft carrier,

both points being spaced from the tip thereof, and a guide to prevent transverse displacement of said device.

2. In a loom having a magazine, a weft 55 carrier support and releasing device comprising a vertically disposed member having a part extended laterally and pivoted to said magazine near the top thereof, a two-point engaging device adjustably secured to the lower end of said member and engaging a weft carrier in transfer position at two points on the rear side of said weft carrier, both points being spaced from the tip thereof, a guide to prevent transverse displacement of said device, and means to secure said guide to a fixed portion of said magazine, said means permitting adjustment thereof axially of the weft carriers.

3. In a loom having a magazine, a weft 60 carrier support and releasing device comprising a vertically disposed member having a part extended laterally and pivoted to said magazine near the center of the top thereof, and on the outer side thereof, said laterally extended part being offset near its outer end, and a two-point engaging device at the lower end of said member, engaging a weft carrier in transfer position on the rear side 65 of points spaced from the tip thereof.

4. In a loom, a magazine, a unitary weft 70 carrier support and releasing device therefor comprising two weft carrier engaging members, means to relatively angularly adjust said members and secure them in fixed relation to each other, and means to adjust said members simultaneously vertically relative to said magazine.

5. In a loom, a magazine, a unitary weft 75 carrier support and releasing device therefor comprising two weft carrier engaging members, means to relatively angularly adjust said members and secure them in fixed relation to each other, and means to adjust 80 said members simultaneously vertically relative to said magazine, said latter adjusting means being also effective to vary the position of said engaging device toward and from a weft carrier in transfer position.

In testimony whereof we have hereunto affixed our signatures.

AUGUSTIN J. CHEVRETTE,
EPPA H. RYON,
